UNITED STATES PATENT OFFICE.

RALPH R. BEAL, OF PALO ALTO, CALIFORNIA, ASSIGNOR TO AUGUSTUS TAYLOR, OF SAN FRANCISCO, CALIFORNIA.

RADIOTELEGRAPHY.

Application filed February 19, 1920. Serial No. 360,000.

To all whom it may concern:

Be it known that I, RALPH R. BEAL, a citizen of the United States, and a resident of Palo Alto, county of Santa Clara, and 5 State of California, have invented certain new and useful Improvements in Radio-telegraphy, of which the following is a specification.

The invention relates to radio telegraphy 10 and particularly to radio telegraphy signaling systems.

An object of the invention is to provide a system of single wave radio signaling, in which waves having a frequency above the 15 limit of audibility are converted into signals having a frequency within the range of audibility. Continuous radio oscillation generators, such as the Poulsen arc generator, for instance, produce continuous waves having 20 a frequency above the range of audibility but many receiving stations are not equipped to receive and identify waves of such frequency. This invention, therefore, contemplates so manipulating the high frequency 25 waves, that signals will be received by such stations and this is preferably accomplished by converting the continuous waves into wave trains or wave groups, the frequency of the groups being within the 30 range of audibility, so that signals so transmitted are readily received and identified by all receiving stations.

The invention further contemplates the use of waves of a single wave length, eliminating the compensating wave. Thus, when 35 the signaling key is depressed, a plurality of groups of waves of a single frequency are radiated and when the key is released, practically no radiation occurs.

40 The invention possesses other advantageous features, some of which, with the foregoing, will be set forth at length in the following description where I shall outline in full, that form of the invention which 45 I have selected for illustration in the accompanying drawing, forming part of the present specification. In said drawing I have shown one form of signaling system of my invention, but it is to be understood that I 50 do not limit myself to such form, since the invention, as set forth in the claims, may be embodied in a plurality of forms.

The drawing is a diagrammatic representation of one form of system of my invention.

The system shown comprises a source of continuous oscillations, such as the arc 2, which operates in a hydrogen atmosphere. The arc generator is grounded on one side, preferably the negative, and is connected 60 on the other side to the antenna 3 through the variable inductance 4. Direct current is supplied to the arc generator by the generator 5, and a choke coil 6 is arranged in the positive lead to prevent the flow of radio 65 frequency current to the direct current generator. The arc is subjected to a strong transverse magnetic field, produced by the magnets 7 which are preferably separately excited by the direct current generator 8. 70

Means are provided for varying the electrical constants of the antenna circuit, so that the current therein may be reduced below signaling value. Connected across several of the lower turns of the inductance 75 4 is a circuit 9 containing an energy consuming element and signaling means for controlling the energy losses in such element. The energy consuming element comprises a core 12, formed of stiff iron laminations, 80 which are so chosen to provide a large hysteresis loss, especially at high frequencies. A coil 13 forming part of the circuit 9 is wound on a portion of the core 12 and the current in the coil produces a flux in the 85 core which causes a loss of energy due to hysteresis. This loss varies the electrical constants of the antenna circuit, by effectively increasing the resistance of the antenna circuit to such value that the current 90 therein is reduced below signaling value. By reducing the hysteresis, the losses are reduced and the effective resistance of the antenna circuit reduced, thus increasing the antenna current to signaling value. This 95 loss is reduced by subjecting the core to a magnetomotive force produced by a coil 14 wound on a portion of the core and arranged in circuit with an alternating current generator 15, the frequency of the generator being 100 within the range of audibility, for instance, 500 cycles. A signaling key 16 is arranged in the circuit of the generator 15 and choke coils 17 are preferably arranged between the alternator and the coil 14, to prevent the 105 high frequency current generated in the coil from passing to the alternator. The size of the coil 14 and the alternator are preferably such that when the key is closed, the core is 110 saturated, at intervals depending upon the

alternator frequency thereby reducing hysteresis losses in the circuit at such frequency. When the key is closed, groups of radio frequency waves are radiated from the antenna, the group frequency being the frequency of the alternator and the groups are separated by periods of practically no radiation.

I claim:

- 10 1. In a radio transmission system, a source of oscillations, a transmitting circuit connected to the source, a magnetic core, means connected to the transmitting circuit for impressing on said core a flux in accordance with the current supplied to the transmitting circuit, and means for substantially varying the core losses in the core, whereby signaling may be accomplished, comprising means for impressing on said core an audio frequency flux.
- 15 2. In a radio transmission system, a source of oscillations, a transmitting circuit including an inductance connected to the source, a magnetic core, a winding on said core connected to the transmitting circuit inductance, and means for varying the core losses in said core to a substantial degree, comprising means for superimposing an audio frequency flux on the core.
- 20 3. A radio telegraphy signaling system comprising means for generating a continuous oscillatory current of undamped radio

oscillations, an antenna circuit connected to said means, a signaling circuit, a key in said circuit, means in the signaling circuit operative to permit radiation from the antenna circuit only when the key is closed and means in the signaling circuit for dividing the radiated waves into spaced groups.

4. A radio telegraphy signaling system, comprising a source of continuous radio oscillations, an antenna circuit connected to said source, an inductance in the antenna circuit, a circuit shunting a portion of said inductance, a stiff iron laminated core, a coil in the shunt circuit wound on said core, a second coil wound on said core, and an alternator and signaling key in circuit with said second coil.

5. A radio telegraphy signaling system, comprising a source of continuous radio oscillations, an antenna circuit connected to said source, an inductance in said antenna circuit, a circuit shunting a portion of said inductance, means in the shunt circuit for producing hysteresis losses, and means for varying said losses at audio frequency.

In testimony whereof, I have hereunto set my hand at Palo Alto, California, this 11th day of February, 1920.

RALPH R. BEAL.
